1

The present invention relates to an apparatus designed to determine at any given moment the state of at least one periodically recurring occurrence, assuming that the duration of the period and the starting time of the periodical occurrence are known. This determination is achieved through calculation of a number characterising the state inquired into; the calculation consists of consecutive addition and subtraction of numbers characterising the starting moment of the occurrence and the time at which it is desired to determine the state of the said occurrence. The calculating process is automatically carried out by switching step by step at least one indicating organ in dependence on the position of other organs set from hand in accordance with the data supplied. The apparatus is characterised in such a manner that the extent of the shifting of the indicating organ corresponds to the complement of the number characterising the state it is desired to determine—to a number fixed in advance. Thus is obtained the propulsion in one single direction of the indicating organ for carrying out subtractions as well as additions. The indicating organ is inscribed in such a way that the state of the periodically recurring occurrence it is desired to determine can be ascertained by direct reading.

The numbers serving as basis for the calculation, characterising the starting time of the periodically recurring occurrence and the time at which it is desired to ascertain the state of the said occurrence, are so-called "characteristics," i. e., a kind of "code numbers," co-ordinated to the data, i. e., points of time, given. The significance of these characteristics shall be explained by way of example before describing fully a performed model of the apparatus.

It is assumed that the periodical occurrence contains a certain number of full days. Assuming the start of the occurrence to fall in a given day T_0 , the number p —characterising the state it is desired to ascertain for any one day T_x —is given by the formula:

$$p = T_x - T_0 \quad (1)$$

In the example shown in Fig. 1 of the enclosed drawing the start of a periodically recurring occurrence falls on the eighth day of a month. The period T of this occurrence is supposed to be 23 days, by way of example. If it is desired to determine the state of this occurrence on the 14th day of the same month the number characterising this state according to the Formula 1 will be: $p = 14 - 8 = 6$. This means that on the 14th day

of the month the occurrence has reached the sixth day of its period.

The calculation is more difficult when the period of time which has elapsed from the start of the occurrence includes any arbitrary number of days. In this case the number p characterizing the state of the occurrence on any one day T_x will be found by using the formula:

$$p = (T_x - T_0) k \cdot T \quad (2)$$

- 10 in which k represents the number of full periods. Should, for instance, the occurrence start on 5th January 1941 and the period last 23 days—the state of the occurrence on 7th June 1941 will be calculated as follows: $p = (158 - 5) - 6 \cdot 23 = 15$. The difference $(158 - 5)$ represents the number 15 20 of days elapsed between 5th January and 7th June. The factor $k = 6$ gives the number of full periods within this interval of time. Should this interval of time extend over several years, months and days, the calculation becomes naturally still more complicated and the direct determination of the numbers characterising the state of the periodical occurrence on a given day a more difficult matter. For this reason another 25 method using the characteristics mentioned at the outset has been selected. The determination of these characteristics is effected any zero time fixed in advance. The difference between the 30 two characteristics gives the value characterising the state of the occurrence. This method, working with characteristics, shall be more particularly explained in connection with the example described above. 1st January 1941, 0 o'clock 35 a. m. has been selected as zero time. On 31st January 24 o'clock one full period of 23 days and $31 - 23 = 8$ days will have elapsed. On 28th February one period and $8 + 28 = 36$ days will have elapsed, i. e., 1 period + 1 period + 13 days, or 2 40 full periods + 13 days. On 31st March the time elapsed since 1st January amounts to 3 full periods + 21 days; on 30th April—to 5 periods + 5 days; on 31st May—to 6 periods + 13 days. For the interval ending on 7th June—7 more days are 45 to be added, i. e., $6 \times 23 + 20$ days have elapsed since 1st January. Since, however, the occurrence did not start on 1st January, but on 5th January, 5 days have to be deducted. This results in the number p characterising the state of 50 the occurrence on 7th June being ascertained as $p = 20 - 5 = 15$. The above mentioned numbers 8, 13, 21, 5 and 13 are selected as characteristics for all dates falling on the months of February, March, April, May and June. The month's characteristic can thus be defined as the number re-

sulting from the number of days between 1st January and the first day of each particular month—after subtraction of the number of the days included in the full periods. These characteristics can be calculated in advance, not only for the months, but also for the days of the month, for the years, decades, centuries, etc. Thus, to determine the state of a periodical occurrence at any given moment it is not required any longer to calculate the total number of days elapsed between the starting moment of the occurrence and the moment in which the state of the periodical occurrence shall be determined; the only data required are the characteristics of the starting moment and of the moment for which the state shall be determined.

According to the above definition the January characteristic is zero where zero time falls on 1st January, 0 o'clock. In leap-years the 29th February has, of course, to be specially considered. In this case the characteristic for March is no longer 13, but 14. The characteristics of the months March to December inclusive in leap-years exceed by one unit each the characteristics of the same months for ordinary years. The result remains naturally the same if the characteristics for January and February are reduced by one unit each instead. This is connected with a slight simplification in the practical design of the apparatus, since leap-years have to be paid special consideration in the case of two monthly characteristics only, instead of ten.

The following table is a compilation of the monthly characteristics:

Table I

Month	Characteristics	
	Normal year	Leap-year
January	0	0 or -1
February	8	8 7
March	13	14 13
April	21	22 21
May	5	6 5
June	13	14 13
July	20	21 20
August	5	6 5
September	13	14 13
October	20	21 20
November	5	6 5
December	12	13 12

Similar tables can now be compiled for the other time divisions. Up to the period duration the characteristics of the days of the month correspond to the order numbers of the days themselves. Beyond this the period duration has to be deducted. For a periodical occurrence with a 23 day-period, for instance, the characteristic for the 25th day of a month equals $25 - 23 = 2$, when—as is advisable—zero time for the daily characteristic falls on the first of the month. By means of these characteristics the state of the periodical occurrence in the example selected can be very easily determined from the difference between the characteristics of the days and months, as follows:

$$p = (T_x + M_x) - (T_0 + M_0), \quad (3)$$

in which formula the daily characteristics are designated by T , and the monthly characteristics by M . For the 5th January $T_0 = 5$, $M_0 = 0$; for the 7th June $T_0 = 7$, $M_0 = 13$. It follows that:

$$p = (7 + 13) - (5 + 0) = 20 - 5 = 15$$

The determination of the characteristics for

the yearly units, decades and centuries, etc., presents no particular difficulties. For instance, the characteristic for the yearly unit zero is fixed at zero; it follows that the characteristic for the year 1 will be 20, since $365 - 15 \cdot 23 + 20$. The leap-years must, of course, be taken into account here too, duly taking in consideration the fact that certain decades include 2 leap-years, and others 3 leap-years. If we split up any number of indicating a year into units and decades the matter of the leap-years can be accurately circumscribed, since the odd decades contain two, and the even decades three leap-years each. The following tables can now be evolved for the characteristics of the yearly units and decades to be determined in advance:

Table II

Yearly units	Characteristic E	
	odd decades	even decades
0	0	0
1	20	20
2	18	17
3	15	14
4	12	12
5	9	9
6	7	6
7	4	3
8	1	1
9	21	21

Table III

35	Decade	Characteristic Z	Decade	Characteristic Z	Decade	Characteristic Z
	170	0	180	0	190	0
40	171	18	181	18	191	18
	172	14	182	14	192	14
	173	9	183	9	193	9
	174	5	184	5	194	5
	175	0	185	0	195	0
45	176	19	186	19	196	19
	177	14	187	14	197	14
	178	10	188	10	198	10
	179	5	189	5	199	5

With the assistance of the data supplied by the above tables it is now possible to determine, for a periodical occurrence with a 23 day-period, the state of this occurrence at any time between 1st January 1700 and 31st December 1999, assuming of course that the starting moment of the periodical occurrence also falls within these limits.

If we designate the characteristics for days, months, yearly units and decades with T_x , T_0 , M_x , M_0 , E_x , E_0 , Z_x , Z_0 respectively—the state of the periodical occurrence will be determined by the general formula:

$$p = (T_x + M_x + E_x + Z_x) - (T_0 + M_0 + E_0 + Z_0) \quad (4)$$

We shall now give a further example of the working of this method for determining by means of characteristics the state of a periodical occurrence at any given moment. We assume the starting moment of the periodical occurrence to fall on 8th November 1738. What is the state of the periodical occurrence on 6th February 1793? We extract from the above tables the following characteristics for the respective days, months, yearly units and decades: $T_0 = 8$, $M_0 = 5$, $E_0 = 1$ and $Z_0 = 9$; $T_x = 6$, $M_x = 8$, $E_x = 15$, $Z_x = 5$. Therefrom follows:

$$p = (6 + 8 + 15 + 5) - (8 + 5 + 1 + 9) = 34 - 23 = 11$$

On 6th February 1793 the periodical occurrence is in the 11th day of its period. When checking this result we find that between 8th November

1738 and 6th February 1793 54 years, 2 months and 29 days have elapsed, therefore in the aggregate, including 14 leap-days, 19'814 days. During this interval of time 861 $1\frac{1}{2}$ periods have elapsed, i. e., periodical occurrence is actually in the 11th day of its period. This tallies with the result of the above calculation achieved by means of characteristics.

All the examples given refer to an occurrence with a 23 day-period. There is, of course, nothing to prevent the same method from being used for determining the state of occurrences with another period duration. There are, of course, different characteristics for each period duration.

As can be noticed from the Formula 4 the value p characterising the state inquired into is represented by the difference between two values. In order to comply with the requirement that the indicating organs of the apparatus designed to carry out the calculating process should be switched step by step in one single direction, the indicating organ will be shifted to the extent corresponding to the complement p' of the value p to a fixed number K , not to the extent corresponding to the value p itself. Instead of the Formula 1

$$p = T_x - T_0$$

we determine the value:

$$p' = T_0 + (K - T_x) \quad (5)$$

By comparing the formulas 1 and 5 we get:

$$p' = K - p \quad (6)$$

Theoretically, the value K may be represented by any positive number. It is advisable in practice to select K as small as possible so as to limit the pitch range. In view, however, of the necessity of complying with the requirement of switching in one direction the value selected for K may not be smaller than the greatest possible characteristic. This means that it will be advisable to equal K to the period duration.

The indicating organ is not inscribed with the values of p' , but with those of p so as to find the result p by direct reading. Since the registering organ is switched forward in one direction for the two data given, it is possible to use, for building up the apparatus, elements of automatic telephony, such as relays and step-by-step switch selectors.

The enclosed drawing shows a constructional example of execution of the apparatus according to the present invention, as described below.

Fig. 1 serves to explain the calculating process.

Fig. 2 is a view from above of a constructional example of an apparatus according to the invention.

Fig. 3 is a schematical cross-section of this constructional example along the line III-III of Fig. 2.

Fig. 4 shows the reading scales enlarged.

Fig. 5 is a diagram of connection of the constructional example.

The apparatus described below serves for determining simultaneously the state of three different periodical occurrences. The period of the first occurrence is 23 days, of the second one—28 days, and of the third one—33 days. The apparatus has a range sufficient to investigate these periodical occurrences within the time interval between 1st January 1700 and 31st December 1999.

To set the two data supplied (start of the occurrence and time for which the state of the occurrence is to be determined) four hand-operated switches are used: 1, 2, 3 and 4 (Fig. 2). Of

these, the first one serves to set the day number, the second one—the month, the third one—the decade, and the fourth one—the yearly unit. The splitting up of the number indicating the year into yearly units and decades makes the use of simple hand-operated switches possible. The data corresponding to the setting of these switches appear behind small windows on the actuating switch-board. The determination of the state of the occurrence now takes place in accordance with the Relation 4 previously mentioned. The hand-operated switches are designed as rotary step switches, each step being connected by wire—in a manner partly to be seen in Fig. 5—with the contact plate of a step-by-step switching rotary selector D acting as guiding selector. Two push-keys Ta_1 and Ta_2 , respectively, are used for starting the apparatus for registering the first and second sum, respectively, of the difference p . The apparatus can be set back to zero position by means of key Ta_3 . A signal lamp BL lights up during the setting and registering process.

The reading device (Fig. 4) is arranged besides the switch board provided with switch buttons, lamp and keys. There are five scales side by side: "M," "date," "W," "day" and "I." The scales "M," "W" and "I" are fitted on the endless strips 5 (Fig. 2) which are switched forward step by step in the direction indicated by the arrow P. These strips are inscribed with numbers indicating the period days of the different occurrences. Positive and negative half of the periods are coloured differently so as to be distinguished more clearly. In the drawing, Fig. 4, each positive part is provided with black rims.

The "date" scale contains the daily dates 1-31 and is fixed. The "day" scale contains the names of the week-days and is made to slide to and fro (arrow P1) so as to be brought to coincide with the "date" scale according to the date to be controlled. For this purpose a table, e. g., written at the place 18 below scales, may be used. Eventually a calendar for the running and perhaps of the neighbouring years is quite sufficient.

The strips 5, preferably 16 mm. ($1\frac{1}{16}$ in.) film strips, are stretched on two rollers 6 and 7 each (Fig. 3); the one, 6, is geared and influenced by a step-by-step switched electro-magnet 8. This electro-magnet controls an armature 9 with an arm 10 carrying a pawl 11 and bringing this latter into engagement with a gear wheel 12. This gear wheel 12 is rigidly coupled with the roll 6. A cam disc 15 actuated by the roll 6 over a reduction gear 13, 14 controls an alternating contact 16. The transmission ratio of the gear is such that the cam disc accomplishes a full revolution when the strip is switched forward for as many steps as correspond to a period. The length of each strip must be such that it corresponds to an entire multiple of periods. For the strip M this revolution corresponds to 23, for the strip W—to 28, and for the strip I—to 33 steps. The contacts 16 controlled by the cam discs serve to bring automatically the strips into position of rest. This is characterised by the fact that the figure (number) 1 of each strip is standing at the same height as the figure 1 of the "date" scale. The armature 9 of each step-by-step switching magnet controls moreover a working contact 17 whose function shall be explained later. Each strip must be as long as to run over its whole length when switched forward over so many steps as one or several complete periods contain. Thus each

strip is at least as long as the distance of so many scale-divisions as the corresponding period, respectively several complete periods, contain. Of course this entire number of periods must be at least so large as to allow each strip to cover at least its scale window. Thus the strips M, W and I have different lengths generally, and consequently request different axle-distances of the different roll-couples 6, 7.

The diagram of connections of the apparatus shall now be briefly described with the help of Fig. 5. In Fig. 5 all relay contacts are, in the conventional manner, in the resting, unexcited position. The hand-operated switches 1 and 2 are each provided with three contact rows TI to TIII, and MI to MIII, respectively; the hand-operated switches 3 and 4—each with four contact rows ZI to ZIV, and EI to EIV, respectively. The contact rows I to III of each hand-operated switch are connected by wire with the contact rows swept by the selector arms dI, dII, dIII of the rotary selector D acting as guiding selector. In Fig. 5 only those wire connections are shown that are required for demonstrating one example of calculation. Between the contact rows ZIV to EIV of the hand-operated switches 3 and 4 an additional special connection is provided including 3 relays J1, J2 and S by means of which it is possible to make corrections in the results obtained. These corrections serve to take leap-years into account. In order to keep the number of contacts on the relays J1 and J2 as low as possible the characteristics for the months of January and February are reduced by one unit for leap-years, as previously explained. This means that the characteristics contained in the third column of Table I are being applied. The step-by-step switching electromagnets for the forward switching of the strips are designated with M, W, I. The corresponding set-back contacts are designated with m0, w0, i0, the armature contacts with m, w, i. A twelve step controller switch St with arms stI to stVIII also fulfills a few switching functions which shall be explained later on with the help of an example of calculation. Several relays C, F, U, V, Pm, Pw and Pi serve furthermore for establishing various circuits.

The first step of the hand-operated switch Z coincides with the 170th decade . . . step 10 to decade 179 . . . step 30 to decade 199. The first step of the hand-operated switch E corresponds to the year zero . . . the 10th to the 9th year unit.

The working of the apparatus shall now be described with the assistance of a sample calculation. We are assuming that three periodical occurrences M, W, I with a 23 day-, 28 day- and 33 day-period, respectively, started simultaneously on 8th November 1738. The state of these periodical occurrences on 6th February 1793 is to be determined.

For each of these two numbers characterising the time (date) the following Table IV contains in the columns "step" the respective contact number (step) upon which each of the switches 5 T, M, Z, E has to be set by hand. The numbers in the columns dI, dII and dIII are deduced from the above-mentioned "characteristics" (characteristical numbers) and mark the wire-connections of the hand-operated switches with those contacts of the guiding selector, which cause the switching-electromagnets M, W and I to stop regarding the initial date of 8th November 1738 respectively to start regarding the final date of 10 6th February 1793. These switching-occurrences 15 will be described more particularly below.

It happens that certain wire-connections pass over alternative contacts S1, S2, S3 (in resting position for our example) resp. i1, i2, i3 (in "make" position for our example); these connections are marked in the Table IV. The operating circuit for the connected-in-parallel relays J1 and J2 actuating the contacts i1, i2 and i3 is prepared by the switch Z having been set by hand into position 10 (corresponding to decade 179), 20 as above-mentioned. The below-described circuit 25 shows how this operation will be started.

The wire-connection-numbers in the columns dI, dII and dIII are deducted from the above-mentioned "characteristics" as follows: Each 30 day's characteristic must be reduced by one unit, whereas five units are added to each monthly characteristic for allowing the practical fabrication of the wire-connections to be realizable. 35 For 8th November 1738, i. e., the day's characteristic 8 is to be represented by the 7th selector's contact, while to the month's characteristic 5 corresponds the 10th selector's contact for a period of 23 days. For 6th February 1793 the 40 characteristics undergo the same translations; 6 to 5, resp. 8 to 13, etc.

With reference to the decades and yearly units, and as far as the periodical occurrence with the 23 day-period is concerned, the selector steps coincide with the characteristics indicated in Tables II and III. The characteristics corresponding to the occurrences with 28 day- and 33 day-period, and consequently the number of steps indicated in the columns dII and dIII, have been ascertained in the same manner as those of column dI.

The former Equation 4 thus is transformed into:

$$55 p = [(T_x - 1) + (M_x + 5) + (E_x + Z_x)] - [(T_0 - 1) + (M_0 + 5) + (E_0 + Z_0)] \quad (4a)$$

which shows that the difference p is changed in no wise, because the translation values 1 and 5 annul themselves because of subtraction. All following calculations refer to Formula 4a).

Table IV

												(working pos.)	

The same principles allow to extend the Table IV for the wire-connections all together. According to Table I each month's characteristic may be one unit larger or smaller for leap years with regard to normal years; thus each contact of the hand-operated switch M is to be connected alternatively to one or the other of two consecutive contacts of the guide-selector, over switches S₁, S₂, S₃ . . . The wire-connections of the contact rows IV of the hand-operated switches Z and E, completely drawn in Fig. 5, shows without difficulty those switch positions which allow an excitation of the relay S for reversing the switches S₁ . . . in concordance with Table I. According to Table II, several year characteristics are one unit larger for odd decades with regard to even decades; thus the corresponding contacts of the hand-operated switch E are to be connected to couples of contacts of the guide-selector. According to Fig. 5 and Table II an excitation of the relays J₁ and J₂ for reversing the switches S₁ . . . is only possible if the arm IV of the switch Z is posed on odd decade-numbers. More details are mentioned in the description of our example of switching occurrences.

The four hand-operated switches are set according to the first date and the key T_{a1} depressed. The relay C responds:

- (1) Earth, controller arm stVII in zero position, key T_{a1}, contact v2, windings I and II of relay C, battery.

Relay C keeps itself actuated over its own contact c3. By reversing the contact c2 a circuit is established for the relay F:

- (2) Earth, contact c2, selector arm dIV in position 35, controller arm stVI in zero position, contact st, relay F, battery.

Each time the relay F is excited the step-by-step switching coil St of the controller gets a current impulse:

- (3) Earth, contacts u2, f2, coil St, battery.

The controller is switched one step and takes up position 1. The contact st switches off the relay F, which, on his part, disconnects St by means of f2. By means of st VII and too by letting loose T_{a1} the circuit (1) is interrupted twice. The coil D of the guide selector is now excited over:

- (4) Earth, contacts c3, f4, controller arm stVIII in position 1, contact u6, coil D, battery.

The coil D attracts its armature and keeps this one by its own contact d2 and the selector arms dI to dV take up position 0. The armature contact d1 excites the relay U:

- (5) Earth, contact d1, relay U together with the resistance W₁₁ connected in parallel and condenser K₀ battery.

Contact u6 switches off coil D. This latter and the relay U are acting together as automatic circuit-breakers, and the selector arms dI to dV are switched forward step by step. The relay U is provided with a damping winding which, together with the resistance W₁₁ and the condenser K₀, acts in such a manner that the switching forward of the selector takes place at a definite rate of speed. With each step of the selector the electromagnets M, W and I are simultaneously excited over the contacts u3, u4 and u5, so that the strips 5 actuated by these magnets are shifted each time by one division in the direction

indicated by the arrow P. The switching magnets M, W and I are excited over the circuits:

- 5 (6) Earth, controller arm stVII in position 1, contacts pm2 and u3, coil M, battery.
 (7) Earth, controller arm stVII in position 1, contacts pw2, c4, u4, coil W, battery.
 (8) Earth, controller arm stVII in position 1, contacts pi2, c5, u5, coil I, battery.

10 As soon as the selector arm dI reaches the position 7, circuits are established for the test relays P_m, P_w and P_i:

- 15 (9) Earth, contact c1, controller arm stIII in position 1, arm TIII of the hand-operated switch in position 8, guiding selector's arm dI in position 1, winding I of the relay P_m, resistance W₁₂, battery.
 20 (10) Earth, contact c1, controller arm stII in position 1, arm TII of the hand-operated switch in position 8, selector arm dII in position 1, winding I of the relay P_w, resistance W₁₃, battery.
 25 (11) Earth, contact c1, controller arm stI in position 1, arm TI of the hand-operated switch in position 8, selector arm dIII in position 1, winding I of the relay P_i, resistance W₁₄, battery.

The three relays P_m, P_w and P_i respond and hold:
 30 (12) Earth, selector arm dV on segment 1-34, rectifier G1 3, contacts c6, pi3, winding I of the relay P_i, resistance W₁₄, battery.
 35 (13) Earth, selector arm dV on segment 1-34, rectifier G1 3, contact c6, rectifier G1 2, contact pw3, winding I of the relay P_w, resistance W₁₃, battery.
 (14) Earth, selector arm dV on segment 1-34, rectifier G1 3, contact c6, rectifiers G1 2 and G1 1, contact pm3, winding I of the relay P_m, resistance W₁₂, battery.

By reversing the contacts pm2, pw2 and pi2 the circuits 6, 7 and 8 are interrupted, thus stopping the strips M, W and I. On the other hand, the selector goes on rotating and after one full revolution the selector arms dI to dV come back to position 35.

The relay F is excited:

- 50 60 (15) Earth, contact c2, selector arm dIV in position 35, momentarily closed contact u1, controller arm stVI in position 1, contact st, relay F, battery.

As a result of the response of the relay F the controller is switched forward into position 2. The selector starts a new revolution and comes into position 0. Under the locking effect of the rectifier G1 4 the holding circuits 12, 13 and 14 of the relays P_m, P_w and P_i are interrupted. The relay armatures drop down, so that the contacts pm2, pw2 and pi2 are set back, thus re-establishing the circuits 6, 7 and 8.

65 The guiding selector D carries out one complete revolution. After it has reached the first step, the relay P_w is excited:

- (16) Earth, contact c1, controller arm stII in position 2, arm MII of the hand-operated switch in position 11, selector arm dII in position 1, winding I of the relay P_w, resistance W₁₃, battery.

The relay P_w keeps itself actuated in the circuit 13. By reversing the contact pw2 the circuit 7 is interrupted and consequently the strip 75 having been actuated by the switching magnet

W is stopped. The selector goes on rotating and the two strips M and I are switched forward until the arms dI to dV reach the tenth step; the relay Pm then responds:

- (17) Earth, controller arm $stIII$ in position 2, arm $MIII$ of hand-operated switch in position 11, selector arm dI in position 10, winding I of the relay Pm , resistance $Wi2$, battery.

The relay Pm reverses its contact $pm2$ and keeps itself actuated over the circuit 12. The strip having been actuated by the magnet M is stopped. The selector D goes on rotating and the strip actuated by the magnet I is alone switched forward until the arms dI to dV reach the twelfth step; the relay Pi then responds:

- (18) Earth, contact $c1$, controller arm stI in position 2, arm MI of hand-operated switch in position 11, selector arm $dIII$ in position 12, winding I of the relay Pi , resistance $Wi4$, battery.

The relay Pi stays in the circuit 14 and reverses its contact $pi2$, thus stopping the strip I. The selector goes on rotating until its arms dI to dV reach step 35. The controller is switched forward in the manner already described and comes into position 3. The selector arm dV , arriving in position 0, switches off the three relays Pm , Pw and Pi . During the third revolution of the selector three processes similar to those just described take place. With the selector in position 1 the relay Pi is again excited over the controller arm stI in position 3, the arm ZI of the hand-operated switch in position 4 and the selector arm $dIII$. The strip corresponding to the magnet I has just been going forward one step. After the selector has reached the ninth step the relays Pm and Pw respond simultaneously. Only on completion of the third revolution is the controller brought into position 4 by the arm dIV . In position 0 the arm dV causes the relays Pm , Pw and Pi to drop in the manner already described. The selector starts a new revolution and, in position 1, the relay Pm , over the arms $EIII$ in position 1, is made to respond.

After the tenth position the selector causes the relay Pw to respond; after the 18th position—the relay Pi . At the end of the fourth revolution the arm dIV brings the controller St into position 5. The registering process of the first date is now completed. The forward switching circuit 4 of the selector D is now interrupted by the controller arm $stVIII$ in position 5.

The strip M was thus shifted $7+10+9+1$ steps in the direction of the arrow P4. The aggregate characteristic for the starting day of the periodical occurrence K_{0M} is therefore found to be:

$$(K_{0M}+4) = (T_{0M}-1) + (M_{0M}+5) + Z_{0M} + E_{0M} = 7+10+9+1=27 \quad (7)$$

Since the period is of 23 days, the actual shifting of the strip M amounts, however, to $K_{0M}+4=27-23=4$ steps.

The strip W was shifted $7+1+9+10$ steps:

$$(K_{0W}+4) = (T_{0W}-1) + (M_{0W}+5) + Z_{0W} + E_{0W} = 7+1+9+10=27 \quad (8)$$

The shifting of the strip I amounts to 38 steps as follows:

$$(K_{0I}+4) = (T_{0I}-1) + (M_{0I}+5) + Z_{0I} + E_{0I} = 7+12+1+18=38 \quad (9)$$

Since the period of the third occurrence is 33

days the actual shifting of the strip I amounts to $K_{0I}+4=38-33=5$ steps.

The hand-operated switches 1 to 4 shall now be set according to the date 6th February 1793.

- 5 The key $Ta2$ is depressed, the relay F excited:
- (19) Earth, key $Ta2$, controller arm $stVI$ in position 5, contact st , relay F , battery.

The controller is brought into position 6. The forward switching circuit 4 for the selector is re-established by the arm $stVIII$ and the selector D carries out four new consecutive revolutions. Since the controller arm $stVII$ is in position 6 there are no forward switching circuits for the magnet coils M, W and I, st that the strips stand still. As soon as the selector has completed five steps, the three relays Pm , Pw , Pi which stay over their own contacts $pm3$, $pw3$, $pi3$ in the circuits 12, 13 and 14 are simultaneously excited. As previously described, the exciting circuits of these relays pass through the controller arms $stIII$, $stII$ and stI , the arms $TIII$, TII and TI of the hand-operated switches, newly set, and the selector arms dI , dII and $dIII$. The selector goes on rotating and the three magnet coils M, W and I now receive current impulses over the circuits:

- (20) Earth, controller arm $stVII$ in position 6, contacts $pm2$ and $u3$, magnet coil M, battery.
- (21) Earth, controller arm $stVII$ in position 6, contacts $pw2$, $c4$ and $u4$, magnet coil W, battery.
- (22) Earth, controller arm $stVII$ in position 6, contacts $pi2$, $c5$ and $u5$, magnet coil I, battery.

The selector D goes on rotating until the arm dIV reaches the position 23. The following circuit is now established:

- (23) Earth, contact $c2$, selector arm dIV in position 23, contact $pm1$, winding II of the relay Pm , controller arm $stIV$ in position 6, resistance winding II of the relay V , battery.

The windings I and II of the relays Pm , Pw and Pi are wound in opposite senses. The relay Pm is thrown off when its winding II is excited. By setting back the contact $pm2$ the impulse circuit 20 for the magnet coil M is interrupted and the corresponding strip stopped. The selector, however, goes on rotating until the arm dIV reaches the position 28, whereby current is brought to flow in the winding II of the relay Pw :

- (24) Earth, contact $c2$, selector arm dIV in position 28, contact $pw1$, winding II of the relay Pw , controller arm $stIV$ in position 6, resistance winding II of the relay V , battery.

The relay Pw is also thrown off and the impulse circuit 21 of the magnet coil W is interrupted by setting back the contact $pw2$. In the same manner the excitation of the relay Pi is cut off when the selector arm dIV reaches the position 33. In position 35 the arm dIV causes the controller to be switched forward into position 7 and, when the revolution is completed, the arm dI reaches the position 11. It should be noticed that, at the second setting of the hand-operated switches, the arm ZIV was brought into position 179, which is identical to its 10th contact-step, and the arm EIV into position 4. We have now

to investigate whether the relay S and the relays J₁ and J₂ have been excited. For the relays J₁ and J₂ the circuit:

- (25) Earth, contacts c₃, v₂, arm ZIV of the hand-operated switch in position 179 (i.e., 10th step), relays J₁ and J₂ parallel, battery,

Is only established as and when the winding I of the slow-releasing relay V is put under current through reversing the contact u₂. It does not matter if the contacts i₁, i₂ and i₃ are adjoined to the relay J₁ or J₂, the connection in parallel of two relays, J₁ and J₂, is necessary, because the 12 alternating contacts i cannot be established on one single relay. In position 4 of the arm EIV of the hand-operated switch no circuit is established for the relay S. On completion of the revolution of the selector D the contact s₃ decides whether the relay Pi shall respond over position 2 or over position 3 of the arm dIII. Since the relay S is not under current the contact s₃ is in a position of rest, so that the relay Pi only responds when the arm dIII reaches the step 3. The impulse circuit for the magnet coil I is then established through reversal of the contact pi₂. In position 179 (i.e., 10th step) of the arm ZIV of the hand-operated switch the relays J₁ and J₂ are excited. The contacts i₁, i₂ and i₃ are reversed, the contact i₂ thus deciding that the relay Pw shall only respond when the selector arm dII reaches the step 4. The selector goes on rotating and the arm dI reaches the step 12. Since the relay S has not responded owing to the arm EIV of the hand-operated switch being set on step 4, which is identical with the third year unit, the arm dI gets into position 13. The contact s₁ now causes the relay Pm to respond. During the further rotation of the selector the arm dIV reaches one after the other the positions 23, 28 and 33, so that the armatures of the relays Pm, Pw and Pi drop one after the other. In position 35 of the selector the arm dIV brings the controller into position 8; on reaching the position 8 the arm dII causes the relay Pw to be excited. The impulse circuit for the magnet coil M is established, and the corresponding strip again switched forward. In position 4 the arm dIII excites the relay Pi; in position 5 the arm dI—the relay Pm, so that the magnet coils I and M are actuated one after the other. When the selector arm dIV reaches the positions 23, 28 and 33, the armatures of the relays Pm, Pw and Pi drop one after the other and the strips actuated by the magnets M, W, I are stopped. In position 35 the arm dIV brings the controller into position 9. Arms dII, dIII and dI, on reaching the positions 4, 7 and 15—cause the relays Pw, Pi and Pm to respond one after the other. The strips M, W and I are switched forward until the arm dIV reaches the positions 23, 28 and 33. Thereupon the armatures of the three relays Pm, Pw and Pi drop, thus stopping the strips M, W and I. In position 35 the arm dIV brings the controller into position 10 and the forward switching circuit 4 of the selector is interrupted by the arm stVIII. The strips stay in the positions reached until the key Ta₃ is depressed. It should be noticed that after the second setting of the hand-operated switches and after depressing the key Ta₂, the strips M, W and I do not any longer carry out the number of steps marked on the contact plate by these hand-operated switches, but in each case a number of steps equal to the difference between the numbers marked

and 23, 28 and 33 respectively. The numbers of steps carried out by the strips in the course of the second calculating process are therefore the complements to 23, 28 and 33, respectively, of the numbers indicated by the selector arms. This result is made possible by the arrangement of the controller arms stIV, stVII, of the selector arm dIV, and of the relays Pm, Pw and Pi wound as differential relays. In the course of the second calculating process the strip M was therefore shifted:

$$(23-5) + (23-13) + (23-5) + (23-15) = 54 \text{ steps.}$$

The effective shifting as compared with the initial position thus amounts to $54 - 2 \cdot 23 = 8$ steps. This shifting is automatically added to the shifting $K_{0M} + 4 = 4$ (see Equation 7) derived from the initial date. The total shifting, from the start of the whole process, amounts therefore to 20 4 + 8 = 12 steps. 12 is the complement of 11 to 23; this follows from the relation:

$$p = (K_{xM} + 4) - (K_{0M} + 4) = 15 - 4 = 11$$

wherein $K_{0M} + 4 = 4$ follows again (from Equation 25 7); furthermore K'_{xM} is:

$$(K'_{xM} + 4) = (T_{xM} - 1) + (M_{xM} + 5) + Z_{xM} + E_{xM} = 5 + 13 + 5 + 15 = 38$$

in which 5, 13, 5 and 15 are the numbers of contacts marked on the contact plate by the hand-operated switches. From this sum the period $K = 23$ is to be subtracted:

$$K_{xM} + 4 = (K'_{xM} + 4) - K = 38 - 23 = 15$$

35 The calculation was thus carried out according to the relation:

$$p' = K - p = K_{0M} + [K - (K_{xM} + 4)] = 4 + (23 - 15) = 12$$

40 In the zero-position the numbers 6 of all strips were coinciding with the number 6 of the fixed date scale (equal to the day number of the 6th February 1793). The strip M having been shifted by 12 steps in the complementary sense indicated by the arrow (Fig. 4), the date number 6 is now opposed to the strip number 17. By subtracting these two numbers $17 - 6 = 11$ we get the wanted number $p = 11$ characterising the state y of M inquired into.

45 The same considerations apply to the strips W and I. In the course of the second calculating process the strip W was shifted:

$$(28-5) + (28-8) + (28-0) + (28-4) = 95 \text{ steps}$$

50 The actual shifting of the scale amounts to $95 - 3 \cdot 28 = 11$ steps. To this shifting is to be added: $K_{0W} + 4 = 27$ (from Equation 8). The total shifting from the starting position amounts to $27 + 11 = 38$ steps. It should be noticed, however, that the period W includes 28 units, so that the effective aggregate shifting as compared with the starting position amounts to $38 - 28 = 10$ steps. 18 is the complement of 10 to 28. The condition

$$p' = K_0 + 4 + [K - (K_x + 4)]$$

and

$$p = K_x + 4 - (K_0 + 4)$$

70 respectively, is also fulfilled.

The strip W is scaled so, that the strip number 24 communicates with the fixed number 6 of the "date" scale. From their difference $24 - 6 = 18$ results the wanted number $p = 18$, 75 characterising the state y of W inquired into.

The shifting of the strip I in the course of the second calculating process amounts to:

$$(33-5)+(33-3)+(33-4)+(33-7)=113 \text{ steps}$$

It corresponds to an effective shifting of the scale of $113-3 \cdot 33=14$ steps. This, together with the 5 steps representing the shifting during the first calculating process, according to Equation 9 gives a total shifting of 19 steps. 14 is the complement of 19 to 33. Here again, the relations: 10

$$p=K_x+4-(K_0+4)=19-5=14$$

and

$$p=K_0+4+[(K-K_x+4)]=5+(33-19)=19 \\ (=complement of 14 to 33)$$

are complied with. The strip I is scaled so, that the strip's number 20 communicates with the fixed number 6 of the "date" scale. From their difference $20-6=14$ results the wanted number $p=14$ characterising the state y of M inquired into.

On the basis of the above we arrive at the following solution of the problem:

The three periodical occurrences with periods of 23, 28 and 33 days respectively which all started on 8th November 1738 were, on 6th February 1793, in the following state: The first occurrence in the 11th day, the second occurrence in the 18th day, and the third occurrence in the 14th day of the period.

This can easily be proved. As previously ascertained, the time interval elapsed between 8th November 1738 and 6th February 1793 is 19'814 days. During this interval:

$$\frac{19'814}{23}=861\frac{11}{23}$$

periods of the first occurrence,

$$\frac{19'814}{28}=707\frac{18}{28}$$

periods of the second occurrence, and

$$\frac{19'814}{33}=600\frac{14}{33}$$

periods of the third occurrence, have elapsed.

To pass on to a new calculation the three strips must be put back into their initial position. This is effected by depressing the key Ta3.

The winding I of the relay C is short-circuited and the armature of the relay drops. The following circuit is thus established for the relay U:

(26) Earth, controller arm *stV* in position 10, contact *m0*, contact *m*, relay U, battery.

The forward switching coil M is fed with current over:

(27) Earth, controller arm *stVII* in position 10, contact *u3*, coil M, battery.

The armature contact *m*, designated with 17 in Fig. 3, is opened and the relay U switched off. The contact *u3* thus opened switches off the coil M, the contact *m* is closed. This process is repeated until the strip actuated by the electromagnet M has reached such an initial position as to make correspond the Figure 1 on the strip and the Figure 1 on the "date" scale. Thereupon, the contact *m0* (designated with 16 in Fig. 3) is reversed. The relay F is excited: 70

(28) Earth, contact *c2*, controller arm *stV* in position 10, contacts *m0*, *st*, relay F, battery.

The relay F responds and the contact *f2* causes the controller to be switched forward into posi- 75

tion 11. A circuit is now established for the relay U over the contact *w0*:

(29) Earth, contact *c2*, controller arm *stV* in position 11, contacts *w0* and *w*, relay U, battery.

The coil W is fed with current:

(30) Earth, controller arm *stVII* in position 11, contact *u4*, coil W, battery.

The coil W and the relay U act as relay breakers until the strip actuated by the magnet W has reached a position corresponding to the initial position of the strip M. The contact *w0* is then reversed and the relay F again excited:

(31) Earth, contact *c2*, controller arm *stV* in position 11, contacts *w0*, *st*, relay F, battery.

The controller is switched forward into position 12 and the relay U excited:

(32) Earth, contact *c2*, controller arm *stV* in position 12, contacts *i0*, *i*, relay U, battery.

The coil I is fed with current over:

(33) Earth, controller arm *stVII* in position 12, contact *u5*, coil I, battery.

The strip I is brought step by step into the initial position; the contact *i0* thus reversed switches in the relay F:

(34) Earth, contact *c2*, controller arm *stV* in position 12, contacts *i0*, *st*, relay F, battery.

The controller comes into position 0 and the apparatus is ready to resume work.

Whilst the strips are being put back into initial position the selector D remains unaffected. The relay V responds and holds up its armature in "attracted" position as long as the relay U is active, i. e., as long as the contact *u2* excites the winding VI by impulses. The contact *v1* causes the signal lamp BL to light up. This warns the operator that he shall not perform any manipulation. As soon as the selector, the strips and the controller are stopped the winding I of the relay V remains without current, thus causing the signal lamp BL to go out.

In the case of any mistake in setting the hand-operated switches, making it necessary to put the strips back into initial position before the calculating process is completed, the key Ta3 is to be depressed. The relay C thus short-circuited is caused to drop and the controller occupying any position between 1 and 10 is subjected to current impulses. The relay F is excited:

(35) Earth, contact *c2*, controller arm *stV*, contact *st*, relay F, battery.

The contact *f2* switches in the coil *St* and the controller comes into the next position. The contact *st* switches off the relay F; this latter and the coil *St* act together as circuit-breakers and the controller is switched forward step by step until it reaches position 10. The coils M, W and I are then set to work one after the other in the manner previously described and the corresponding strips are brought back into their initial position. Simultaneously with the dropping of the relay C the selector D is stopped through the opening of the contact *c3*. Current feeding to the coil D of the selector is only resumed when the controller is set to position 0:

(36) Earth, selector arm *dV*, segment 1-34, rectifier *G1 4*, controller arm *st VIII* in position 0, contact *u6*, coil D, battery.

The contact *d1* switches in the relay *U* which together with the coil *D* acts as relay breaker in such a manner that the selector *D* is brought into position 35. The calculating process can now be resumed.

The present invention is not limited to the one constructional example described. Other forms of execution are conceivable, more particularly as far as the inscriptions on the scales are concerned. Instead of using period days the strips could be inscribed with any other value characterising the state *y* of an occurrence *p* under consideration (Fig. 1), e. g., hours, miles or other units of time resp. length. If, for instance, for any strip, the state of an occurrence is a known function of the characterising value, i. e., if, e. g., for each characterising value *p* the value of the state *y* of the occurrence may be expressed by numerical values, it will be possible representing the state *y* of the occurrence. It is also easily possible to indicate these values by relative numbers, for instance in percentages or in a graphical manner.

The chief function of the present invention's apparatus is the automatical calculation of the value *p* characterising the state whereas the additional subjective work of thinking is quite unessential even if the state of the periodical occurrence should be read from a table or graphical diagram separated from the shifted strips.

What is claimed is:

1. Apparatus for the determination of a momentary status of any periodical occurrence, the duration period and the starting moment of which are known, comprising, in combination, a plurality of manually operated setting organs adapted to be moved to one set of positions indicating said starting moment and to another set of positions indicating the time of the momentary status desired, an indicating organ, electromagnetic means for shifting said indicating organ step by step, means connecting said setting organs with said electromagnetic means energizing said electromagnetic means to move said indicating organ automatically a number of steps characterizing said starting moment and further to move said indicating organ a number of steps corresponding to a complement of the value characterizing the momentary status to another value fixed in advance, all in accordance with the position of the above-mentioned setting organs and separate switches connected with the last-mentioned means for initiating the two movements of said indicating organ, and for resetting it to the initial position said two movements being in the same direction.

2. Apparatus for the determination of a momentary status of any periodical occurrence, the duration period and the starting moment of which are known, comprising in combination, a plurality of manually operated setting organs having a plurality of contacts and adapted to be moved to one set of positions indicating said starting moment or to another set of positions indicating the time of the momentary status desired, an indicating organ comprising at least one endless strip having a scale thereon, electromagnetic means for shifting said strip step by step, a rotary selector having a plurality of contacts, means connecting the contacts of said rotary selector with the contacts of said setting organs, means connecting said rotary selector with said electromagnetic means energizing said electromagnetic means to move said indicating organ automatically a number of steps charac-

terizing said starting moment when said organs are in the first-mentioned positions or further to move said indicating organ a number of steps corresponding to a complement of the value characterizing the momentary status to another value fixed in advance, and separate switches connected with the last mentioned means for initiating the two movements of said indicating organ, said movements being in the same direction.

3. Apparatus for the determination of a momentary status of any periodical occurrence, the duration period and the starting moment of which are known, comprising, in combination a plurality of manually operated setting organs having arms and contacts adapted to be selectively engaged by said arms, said arms being adapted to be moved to one set of positions indicating said starting moment or to another set of positions indicating the time of the momentary status desired, an indicating organ, electromagnetic means for shifting said indicating organ step by step, a rotary selector having arms and contacts adapted to be selectively engaged by said arms, means connecting the contacts of said setting organs with the contacts of said selector, means connected with the arms of said selector and said electromagnetic means energizing said electromagnetic means to move said indicating organ automatically a number of steps characterizing said starting moment when said organs are in the first-mentioned positions or further to move said indicating organ a number of steps corresponding to a complement of the value characterizing the momentary status to another value fixed in advance, the last-mentioned means constituting electrical circuits each of which includes an arm of the selector and an arm of a setting organ, and comprising at least one test relay in at least one of said electrical circuits, and separate switches connected with the last mentioned means for initiating the two movements of the said indicating organ.

4. Apparatus for the determination of a momentary status of any periodical occurrence the duration period and the starting moment of which are known, comprising, in combination, a plurality of manually operated setting organs having arms and contacts adapted to be selectively engaged by said arms, said arms being adapted to be moved to one set of positions indicating said starting moment or to another set of positions indicating the time of the momentary status desired, an indicating organ, electromagnetic means for shifting said indicating organ step by step, a rotary selector having arms and contacts adapted to be selectively engaged by said arms, means connecting the contacts of said setting organs with the contacts of said selector, means connected with the arms of said selector and said electromagnetic means and constituting electrical circuits each of which includes an arm of the selector and an arm of a setting organ, and at least one of said electrical circuits comprising at least one test relay, means connected with said relay and said electromagnetic means energizing said magnetic means to provide an intermittent movement of said indicating organ and thereby move said indicating organ automatically a number of steps characterizing said starting moment when said organs are in the first-mentioned positions or further to move said indicating organ a number of steps corresponding to a complement of the value characterizing the momentary status to another value fixed in advance, and separate switches connected

with the last mentioned means for initiating the two movements of the said indicating organ.

5. Apparatus for the determination of a momentary status of any periodical occurrence the duration period and the starting moment of which are known, comprising, in combination, a plurality of manually operated setting organs having arms and contacts adapted to be selectively engaged by said arms, said arms being adapted to be moved to one set of positions indicating said starting moment or to another set of positions indicating the time of the momentary status desired, an indicating organ, electromagnetic means for shifting said indicating organ step by step, a rotary selector having arms and contacts adapted to be selectively engaged by said arms, means connecting the contacts of said setting organs with the contacts of said selector, and means connected with the arms of said selector and said electromagnetic means and constituting electrical circuits each of which includes an arm of the selector and an arm of a setting organ, and at least one of said electrical circuits comprising at least one test relay having an armature and windings adapted to attract said armature or to cause it to drop, and means connected with said relay and said electromagnetic means energizing said electromagnetic means to move said indicating organ automatically a number of steps characterizing said starting moment when said organs are in the first-mentioned positions or further to move said indicating organ a number of steps corresponding to a complement of the value characterizing the momentary status to another value fixed in advance and separate switches connected with the last mentioned means for initiating the two movements of the said indicating organ.

6. Apparatus for the determination of a momentary status of any periodical occurrence the duration period and the starting moment of which are known, comprising, in combination, a plurality of manually operated setting organs adapted to be moved to one set of positions indicating said starting moment or to another set of positions indicating the time of the momentary status desired, an indicating organ, electromagnetic means for shifting said indicating organ step by step, means connecting said setting organs with said electromagnetic means energizing said electromagnetic means to move said indicating organ automatically a number of steps characterizing said starting moment when said organs are in the first-mentioned positions or further to move said indicating organ a number of steps corresponding to a complement of the value characterizing the momentary status to a value characterizing the duration period and separate switches connected with the last mentioned means for initiating the two movements of the said indicating organ.

7. Apparatus for the determination of a momentary status of any periodical occurrence the duration period and the starting moment of which are known, said duration period consisting of a definite number of days, and the time of the momentary status to be determined being removed from said starting moment by any number of years, months and days, comprising a plurality of manually operated switches setting separately numbers corresponding to years, months and days and adapted to be moved to one set of positions indicating said starting moment or to another set of positions indicating the time of the momentary status desired, an indicating

organ, electromagnetic means for shifting said indicating organ step by step, means connecting said switches with said electromagnetic means energizing said electromagnetic means to move said indicating organ automatically a number of steps characterizing said starting moment when said organs are in the first-mentioned positions or further to move said indicating organ a number of steps corresponding to a complement of the value characterizing the momentary status to a value characterizing the duration period, and separate switches connected with the last mentioned means for initiating the two movements of the said indicating organ.

15 8. Apparatus for the determination of a momentary status of any periodical occurrence the duration period and the starting moment of which are known, said duration period consisting of a definite number of days, and the time of the momentary status to be determined being removed from said starting moment by any number of years, months and days, comprising a plurality of manually operated switches setting separately numbers corresponding to decades, individual years, months and days and adapted to be moved to one set of positions indicating said starting moment or to another set of positions indicating the time of the momentary status desired, an indicating organ, electromagnetic means for shifting said indicating organ step by step, means connecting said switches with said electromagnetic means energizing said electromagnetic means to move said indicating organ automatically a number of steps characterizing said starting moment when said organs are in the first-mentioned positions or further to move said indicating organ a number of steps corresponding to a complement of the value characterizing the momentary status to a value characterizing the duration period, and separate switches connected with the last mentioned means for initiating the two movements of the said indicating organ.

9. Apparatus for the determination of a momentary status of any periodical occurrence the duration period and the starting moment of which are known, comprising, in combination, a plurality of manually operated setting organs having arms and contacts adapted to be selectively engaged by said arms, said arms being adapted to be moved to indicate numerals corresponding to said starting moment or to indicate other numerals corresponding to the time of the momentary status desired, an endless strip constituting an indicating organ, electromagnetic means for shifting said strip in one direction step by step, a rotary selector having arms and contacts adapted to be selectively engaged by said arms, conducting wires connecting the contacts of said setting organs with the contacts of said selector, means connected with the arms of said selector and said electromagnetic means and comprising at least one test relay and means connected with said relay energizing said electromagnetic means to move said strip automatically a number of steps corresponding to the first-mentioned numerals or further to move said strip a number of steps corresponding to the complements of said other numerals to numerals corresponding to the duration period, and separate switches connected with the last mentioned means for initiating the two movements of the said indicating organ.

10. Apparatus for the determination of a momentary status of any periodical occurrence the duration period and the starting moment of which are known, comprising, in combination, a plu-

21

rality of manually operated setting organs adapted to be moved to one set of positions indicating said starting moment or to another set of positions indicating the time of the momentary status desired, an indicating organ, electromagnetic means for shifting said indicating organ step by step, means connecting said setting organs with said electromagnetic means energizing said electromagnetic means to move said indicating organ automatically a number of steps characterizing said starting moment when said organs are in the first-mentioned positions, to move said indicating organ in the same direction a number of steps corresponding to a complement of the value characterizing the momentary status to another value fixed in advance, or to move said indicating organ back to its initial position, and three separate switches connected with the last-mentioned means for separately initiating said movements of the indicating organ.

11. Apparatus for the determination of a momentary status of periodical occurrences the duration periods and the starting moment of which are known, comprising, in combination, a plurality of manually operated setting organs having a plurality of contacts and adapted to be moved to one set of positions indicating said starting moment or to another set of positions indicating the time of the momentary status desired, three separate strips constituting separate indicating

22

organs for occurrences of different duration periods and provided with scales inscribed so as to be read simultaneously, electromagnetic means for separately shifting said strips stepwise, a single rotary selector having a plurality of contacts, means connecting the contacts of said rotary selector with the contacts of said setting organs, means connecting said rotary selector with said electromagnetic means energizing said electromagnetic means to move the three indicating organs simultaneously a number of steps characterizing said starting moment when said organs are in the first-mentioned positions or further to move said indicating organs a number of steps corresponding to a complement of the value characterizing the momentary status to values characterizing the duration period, and separate switches connected with the last mentioned means for initiating the two movements of the said indicating organ.
